UNITED STATES PATENT OFFICE.

GLEN PARKS, OF SEATTLE, WASHINGTON.

MACHINE FOR DISTRIBUTING AND DRIVING NAILS.

Application filed February 21, 1924. Serial No. 694,328.

To all whom it may concern:

Be it known that I, GLEN PARKS, a citizen of the United States, residing at Seattle, in the county of King and State of Washington, have invented certain new and useful Improvements in Machines for Distributing and Driving Nails; and I do hereby declare the following to be a full, clear, and exact description of the invention; such as will enable others skilled in the art to which it appertains to make and use the same.

The principal object of this invention is to provide a nail distributing mechanism in conjunction with a machine for nailing metal straps to the ends of wooden slats as disclosed in my patent granted February 19, 1924, numbered 1,484,150. The invention, however, is not limited to the use mentioned, the various features of novelty and invention being set forth in the appended claim.

In the drawings, Fig. 1 is a vertical section through the nail distributing mechanism and so much of the slat-holding means as is necessary to illustrate the application of the nail distributing means.

Fig. 2 is an end elevation looking at the front of the machine.

Fig. 3 is a side elevation of a detail relating to the nail-holding means in conjunction with the work-holding carriers.

Fig. 4 is a vertical sectional view through a portion of the nail distributing device.

Fig. 5 is a plan view of some of the mechanisms shown in Fig. 4.

Fig. 6 is a vertical sectional view through Fig. 4.

Fig. 7 is an elevation of a portion of the mechanism shown in Fig. 8.

Fig. 8 is a view partly in vertical section and in elevation of mechanism shown in Fig. 7.

Fig. 9 is a plan view of a portion of the mechanism shown in Fig. 8.

Fig. 10 is a horizontal sectional view through a portion of the mechanism shown in Fig. 8; and

Fig. 11 is a cross-sectional view of the pulley on which the endless belt shown in Fig. 5 is mounted.

In the drawings, numeral 1 indicates the frame in which is supported a horizontally

disposed shaft 2 having at one end a pulley 3 which is adapted to be connected to any suitable source of power. Secured on the shaft 2 is a pair of slat or work-holding wheels or carriers 4, each wheel or carrier having on its periphery a plurality of jaws 5 within which the slat or work S is held while a metal strap (not shown) is nailed thereto, it being understood that the slat extends from jaw to jaw of the respective work carriers 4.

Each jaw 5 is provided with a radial opening 6 at the bottom of which is a nail-holding device comprising three balls 7 which are pressed toward each other by springs 8, the balls and spring being contained within a removable holder member 9, as more fully shown in Figs. 8 and 10. A plunger 10 is adapted to enter the opening 6 in said jaw to force the nail held between said balls 7 into the work to be nailed. The plunger 10 is secured to a head 11 which is spring-pressed outwardly by means of a spring 12 between said head and jaw, a rod 13 passing through said spring and suitably connected to the head 11 and jaw 5 for holding the head 11 in proper position with respect to said jaw, it being understood that the head 11 is slidable radially in order to permit the plunger 10 to enter and leave the opening 6 in said jaw.

Mounted on the frame 1 is a cam member 14, the same being so disposed with respect to the head 11 on the work carrier that the head will be moved toward said jaw as the carrier rotates (in a counter-clockwise direction as viewed in Fig. 1). Inward movement of the head 11 will, of course, force the plunger 10 into the opening 6 in the jaw for the purpose specified. As shown in Fig. 3 the head 11 to which the plunger 10 is secured may be provided with a plurality of plungers 10 for driving a plurality of nails into the work at one stroke.

The means for feeding the slats into the work-carrying members 4 and for feeding the metal straps over the slats have not been illustrated inasmuch as the same forms no part of the present invention, said mechanism, however, being shown in the patent above-mentioned.

Leading from the opening 6 in each jaw 105 5 is a conduit 15 into which nails are adapt-

ed to be deposited points foremost from a feeding chute 16. The feeding chute 16 comprises a member having a slit in which the body of the nails is received, the heads of 5 the nails resting on the top portion of said chute as clearly illustrated in Fig. 9 wherein said nails are identified by reference character N. Passage of the nails from the feeding chute 16 is controlled by means of a vertically disposed wheel 17 suitably mounted 10 for rotation on a standard 18 forming part of the frame of the machine. The wheel 17 is in the nature of a disk having a plurality of cut-outs 19 through which the 15 nails may pass from the chute 16 to the conduit 15 on the other side of the said wheel. The nails do not pass directly into said conduit 15 after passing through said wheel 17 but are held suspended on a pair of fingers 20 forming in effect a continuation of the chute 16 as more clearly shown in Figs. 8 and 9, the fingers being bent in the direction of rotation of the conduit 15, which latter has a cutaway part 21 in its forward 25 face, the arrangement being such that as the conduit 15 moves beneath the nail suspended on said fingers the nail is pushed off said fingers and dropped into the said conduit 15 and into the opening 6 in the 30 jaw 5 as clearly shown in Fig. 8. The nail-passing wheel 17 has its openings 19 of such shape that picker fingers 22 are provided, the opening between the end of the picker finger and the adjacent portion of the wheel 35 being only sufficient to allow a nail to pass therebetween. The finger 22 is beveled on that face remote from the chute 16 (see Fig. 8) so that after a nail has passed between the opening adjacent the tip of the 40 finger it will be pushed laterally of said wheel onto the nail-holding fingers 20 at the end of the chute. The beveled portion of the finger is indicated by reference numeral 23 in Fig. 8.

45 The nail-passing wheel 17 is adapted to be rotated by the work carrier 4 as the conduit 15 thereon passes the end of the chute 16. The rotating means may conveniently take the form of lateral lugs 24 on the wheel 50 17 which are adapted to be struck by a lateral projection on the conduit 15.

The means for supplying nails to the feeding chute 16 will now be described.

55 As shown in Fig. 2 the conduit 16 is a branched member which extends upwardly forming a single member, the end of which is positioned adjacent the loop 25 of a belt 26 which passes around a pulley 27 at said loop 25 and around a pulley 28 remote there-

60 from in a horizontal direction. The belt 26 is slit longitudinally as at 29 to form a plurality of belt members and to provide an opening into which the body of the nails may be received but not the heads thereof, 65 the heads remaining suspended from the top

of the belt members. The belt members may conveniently consist of a pair of coiled springs arranged side by side, the pulleys 27 and 28 being suitably grooved to hold the spring elements in proper relationship as regards the slit as will be readily understood. The pulley 27 is provided with an annular slot to correspond with the slit 29 in the belt so that the body of the nails may extend down into said annular slot as will be readily understood. As the belt is moved toward the pulley 27 the nails will leave the belt and be received on the adjacent end of the chute 16 as will be readily comprehended by reference to Figs. 4 and 5. After the 80 nails are received on the chute 16 they slide down the same and fill the respective branches constituting the lower end of the chute.

The endless belt 26 is located within a 85 horizontally disposed drum 30, one end of the drum being open as indicated at 31. The interior of the drum is provided with vanes 32 for elevating nails and depositing them on the endless belt 26. As the nails 90 fall on the belt 26 some of them will pass points foremost through the slit 29 therein and be suspended thereon by their heads as shown in Fig. 4. Suitably mounted in fixed relation to the horizontal run of the belt 26 95 is a baffle plate 33 on which the nails are first received after dropping from the vanes 32 within the drum. The nails slide down this plate onto the belt as will be readily understood. Disposed over the lower run of the belt is a second plate 34 which serves to prevent nails from falling thereon. Arranged below the upper run of the belt 26 adjacent the front pulley 27 is a pair of guiding fingers 35 which serve to direct the points of the nails into the annular slot in the said pulley 27.

As shown in Fig. 11 the pulley 27 may consist of independent members having their adjacent faces dished as at 27' to provide 110 clearance for the body of the nails projecting down from the belt.

The drum is supported in any suitable manner in the machine frame and is conveniently driven by rollers 40 suitably geared 115 to a horizontally disposed shaft 41 which is driven from the main shaft 2 by suitable connection as a belt 42.

Arranged at the open end of the drum is an inwardly projecting annular brush 45 120 which is adapted to wipe over the upper run of the belt adjacent the pulley 27 to wipe off any nails which are not properly positioned within the slit 29 of the belt 26.

The pulleys 27 and 28 are maintained in spaced relation by any suitable means as by spacing rods 46. The pulley 27 is mounted on the shaft 41 which, as already indicated, is driven from the shaft 2 by a belt 42.

The drawings show the invention in a 130

more or less diagrammatic manner but the operation thereof will be readily understood from the preceding description.

What I claim is:

5. In combination, a rotatable drum, spaced belt members within said drum providing a slit through which the bodies of the nails may pass but not the heads thereof, means

within said drum for elevating nails and depositing them on said belt members, and a 10 radially disposed brush at the open end of said drum adapted to wipe over the belt members and to dislodge loose nails therefrom.

In testimony whereof I affix my signature.

GLEN PARKS.
